(57) **CLAIM**

The ornamental design of a cream dispenser, as shown and described.

DESCRIPTION

FIG. 1 is a perspective view of a cream dispenser incorporating the design of the invention;

FIG. 2 is a front view of the cream dispenser;

FIG. 3 is a right side view of the cream dispenser with the left side view being a mirror image thereof;

FIG. 4 is a top view of the cream dispenser;

FIG. 5 is a back view of the cream dispenser; and,

FIG. 6 is a bottom view of the cream dispenser.

The phantom lines shown in FIGS. 1–6 are shown for illustrative purposes only and form no part of the claimed design.
